UNITED STATES PATENT OFFICE.

MELZAR L. TERRY, OF INDIAN ORCHARD, MASSACHUSETTS.

PIPE WRENCH.

Application filed February 14, 1922. Serial No. 536,495.

To all whom it may concern:

Be it known that I, MELZAR L. TERRY, a citizen of the United States of America, residing at Indian Orchard, in the county 5 of Hampden and Commonwealth of Massachusetts, have invented certain new and useful Improvements in Pipe Wrenches, of which the following is a specification.

This invention relates to improvements 10 in wrenches and particularly to the type known as pipe wrenches or sometimes they are known in the trade as the Stillson wrench.

An object of the invention is to provide 15 a pipe wrench in which the yoke member is formed with safety guard portions and openings therein which I term safety openings or guard devices to prevent the movable jaw member of the wrench from being 20 moved outward too far thus avoiding the possible breakage of the yoke.

A further object is to provide means for changing or substituting jaw plates of different shapes so that the wrench may be 25 quickly changed and used with flat jaws or faces as a monkey wrench, or with curved plates as a pipe wrench to prevent crushing the pipe when it is gripped by the wrench.

A further object is to provide spring bearing plates on the handle member with which 30 the yoke member engages in order to keep the wrench in proper working position.

A further object is to provide the outer 35 end of the handle member with a curved part for forming a pinch bar.

Referring to the drawings:

Fig. 1 is a side elevational view showing the parts of the wrench assembled and with the triple yoke member attached to the handle member. In this view the gripping jaw plates are shown curved for fitting a pipe also the handle member is shown with a curved end to form a pinch bar.

Figs. 2 and 3 are enlarged views of the 45 inner and outer members of the movable jaw and of the outer end of the handle member, respectively showing the set screws for maintaining the jaw plates in position.

Fig. 4 is a flat or smooth faced jaw plate. 50 Fig. 5 is one with serrations or teeth formed thereon.

Figs. 6 and 7 are side and elevational views, respectively of a curved jaw plate.

Fig. 8 is a modification of the yoke member showing a single guard on the yoke.

Fig. 9 is a further modification of the

yoke showing a double guard as a part of the yoke, and

Fig. 10 is a detail view illustrating the spring bearing pieces with which the yoke 60 members engage.

Referring to the drawings in detail:

1 designates the handle member of the wrench having the forward end portion 2 and the curved pinch bar portion 3. This 65 handle member is formed with grooves 4 for strengthening purposes. 5 designates the movable jaw that is formed with the threads 6. These threads are engaged by the inferiorly threaded adjusting ring or nut 7. 70 8 designates a yoke that is pivotally connected to the bar 1 by means of the pin or bolt 9, whereby the jaw 5 and its supporting yoke may be moved about this point as a center. 7 designates an opening in which 75 the nut 7 is located. The yoke 8 is formed with a safety guard piece 10 which is spaced from the body part of the yoke by the opening 11. A second safety guard member is indicated at 12 which is spaced from the depending portion 13 of the yoke as indicated at 14 and 15 is an additional safety guard member which surrounds the forward lower end of the handle 1. The opening 11 is for 80 the purpose of indicating to the user that the threaded part 6 should not be moved into this opening as there would be danger of breaking the wrench particularly the yoke member 8. 16 designates a removable jaw 85 plate the teeth of which are formed on a curve as shown in Fig. 7 and engaging the 90 curved surface of a pipe or other round piece indicated at 17. This jaw plate is held in place by means of the slideable pin 18 which is moved outward by means of a set 95 screw 19 which screw is formed with a conical shaped end 20 which engages the inclined surface 21 of the pin 18, whereby when the set screw 19 is rotated pin 18 is moved 100 outward against the jaw plate thus clamping it in the dove-tailed shaped groove. The pin 18 is formed with a rib 18' to prevent its rotating, with relation to the set screw 19 or turning out of its position. 22 designates a removable plate in the movable jaw 105 5 which is held in place by means of the set screw 23. 24 (see Fig. 4) designates a jaw plate that is made flat or smooth on its gripping face and which may be substituted for the plates 16 or 22 when the wrench is to be 110 used as a monkey wrench.

For the purpose of maintaining the yoke 8

in working position on the handle, springs 26 are placed on the upper and lower edges respectively of the handle 1. These springs are held in place by means of wedges or 5 other suitable devices, indicated at 20'.

Fig. 8 shows a yoke shaped member in which a single safety guard device is used and the depending part 15 and the upper extending part 10 of the yoke 8 shown in 10 Fig. 1 is omitted.

Fig. 9 shows a yoke the same as Fig. 8 but with the safety guard 10 as well as the guards 12 and 13 but with the portion 15 omitted. These safety guard pieces are for 15 the purpose of preventing the member 8 from being displaced should the pin or bolt 9 break. The curved portion 3 serves as a pinch bar and is in effect a combination tool, combining the wrench and pinch bar construction. By employing the safety guard members, the strain and stresses are equally distributed by the yoke member. Should the part 15 of the yoke 8 break it is clear that the other portions of the yoke would permit it 20 to be used. In other words the safety guard members 10, 12, 13 and 15 serve to permit these portions of the yoke to receive the initial strain when a break occurs, thus serving to prevent a complete breakage of the whole 25 yoke piece.

What I claim is:

1. In a wrench, the combination of a handle member having a dove-tailed groove at the forward end to receive a jaw plate, means 35 for moving the plate outward comprising a slidable pin formed with an inclined end, a set screw engaging said end for moving the plate outward, as described.

2. In a wrench, the combination, of a handle member, an adjustable jaw member 40 separate from the handle member, means for connecting the jaw to the handle, the adjustable jaw member having a dove tailed groove, a removable plate in the groove of the adjustable jaw member, a set screw extending from the outer end of said adjustable member for forcing the plate against the sides of the groove for holding the plate in position, said handle member having a removable plate on its outer end which cooperates with the removable plate in the jaw member.

3. In a wrench of the type described, the combination, of a handle member, a yoke pivotally connected thereto for receiving a 55 movable jaw, springs formed with bent end portions and located on the upper and lower edges of the handle member to provide bearing surfaces for the yoke member for retaining it in operative position for the purpose 60 described, the handle member having openings in which the bent portions of the springs are located.

4. In a pipe wrench, the combination, of a handle member, having a fixed jaw member 65 thereon, said jaw having a grooved recess for receiving an interchangeable plate, a pin extending inward from the plate of the fixed jaw member for engaging the plate for moving the same outward, the pin having an inclined end portion, said pin having a rib thereon for retaining it in position, and a set screw engaging its inclined inner end for moving the pin against the plate for locking the same in position in the recess.

MELZAR L. TERRY.
